(57) **CLAIM**

The ornamental design for a power supply for a battery charger, as shown and described above.

DESCRIPTION

FIG. 1 is a top perspective view of a design for a power supply for a battery charger of the present invention;

FIG. 2 is a top view thereof;

FIG. 3 is a bottom view thereof;

FIG. 4 is a front view thereof;

FIG. 5 is a back view thereof;

FIG. 6 is a right side view thereof;

FIG. 7 is a left side view thereof; and,

FIG. 8 is a bottom perspective view thereof.

The broken lines shown in the drawings are included for the purpose of illustrating environmental structure and form no part of the claimed design.

1 Claim, 7 Drawing Sheets
